HEAT EXCHANGE APPARATUS

Robert Mautsch, Brussels, Belgium, assignor to
 Manufacture Generale Metallurgique, Societe
 Anonyme, Brussels, Belgium, a Company of
 Belgium

Application November 25, 1931, Serial No. 577,328,
 and in Belgium November 28, 1930

7 Claims. (Cl. 257—249.)

The present invention is relative to heat exchange apparatuses such as radiators, evaporators or the like, whose members are constituted by parallel tubes whereon corrugated or puckered fins are threaded. Its object is to provide an improved thermic contact between the fins and the tubes and to strengthen the units assembled of these parts.

For this purpose, instead of making the tubes and the corrugations of the fins of such proportions that only one corrugation of each fin is bisected by the tube passing therethrough, according to this invention fins having close-set corrugations are threaded upon relatively thick tubes so that each of the latter passes through several adjacent corrugations of one same fin. An increased area of contact is thereby obtained between the fin and the tube, said increased area causing the fin to grip the tube more firmly, when the latter is expanded in order to secure the fins thereto, for example. Furthermore, the numerous corrugations at the edge of the hole made in the fin, to allow the passage of the tube therethrough, provide said edge with a greater strength in the direction of said corrugations than is the case if the hole is made in a wider single corrugation, and when the tube is expanded said corrugations so resist distortion of the hole as to cause them to grip the tube tightly, whereby the closest possible contact is secured between the parts.

This invention may be carried into effect in various manners. The fins may be provided with extremely small and close-set puckers, or with larger corrugations sufficiently close-set nevertheless to ensure that each tube shall pass through more than one of them, or groups of small puckers may be caused to alternate with groups of larger corrugations, or again the fin may be so provided with both small and large corrugations that some or all of the latter are themselves puckered and that a tube passing through one large corrugation only, for example, nevertheless bisects several of the small puckers of the fin.

Variations may be made likewise in the arrangement of the corrugated fins relatively to each other. In every case, the fins are arranged in substantially parallel vertical planes, but they either may be so placed as to be spaced from each other or to touch each other, the latter arrangement being preferable since, in that case, no special members are required to keep the fins properly spaced apart before securing them to the tubes. Furthermore, the apices of the corrugations of two adjacent fins may be arranged to face each

other if desired, or the apices of one fin may be caused to face the depressions in the following fin. Likewise, the fins threaded upon the tubes either may all be alike, or fins having small puckers may be caused to alternate, in regular sequence or otherwise, with those having large corrugations.

Some constructional embodiments of this invention are illustrated diagrammatically, by way of example, in the attached drawing, wherein:

Figs. 1, 2 and 3 are plan views of members of a heat exchange apparatus unit, whereof the corrugated or puckered fins are not in contact.

Fig. 4 is a front elevation of one fin, whereof the left hand half is threaded upon a round tube and the right hand half is threaded upon a flattened tube.

Figs. 5 to 9 are plan views of members, whereof the fins are in contact, and

Fig. 10 is a plan view likewise, of a member the large corrugations of whose fins are puckered.

In all the figures of the drawing, *a* denotes the tubes upon which are threaded fins *b* the corrugations *c* of which are sufficiently close-set to ensure that each tube *a* shall pass through several said corrugations of each fin. The corrugations *c* of Fig. 1 have acute angles, whilst those shown in Fig. 2 are rounded and those illustrated in Fig. 3 are of polygonal cross-section. In these three examples the fins *b* are not in contact with each other, and the apices of the corrugations of one fin face the depressions in the corrugations of the following fin, but it is manifest that said fins might be applied against each other and their corrugations be arranged apex to apex to form a kind of honeycomb, as shown in Fig. 5. In this figure the corrugations *d* of the fins are deeper than in the preceding figures, but are nevertheless still sufficiently close-set to ensure that each tube shall pass through several of them in each fin.

Fig. 6 illustrates a preferred embodiment wherein fins *b*, provided with groups of puckers *c* alternating with corrugations *d*, are so arranged that the puckers *c* are situated at the points of the fin which are pierced by tubes *a*, whilst corrugations *d* are in the middle portion of the fin between the tubes, and in the outside portions thereof on either side of the tubes. The fins are thus only in contact with each other at the apices of their major corrugations *d*, this arrangement having over that of Fig. 5 the advantage that the fluid flowing between said fins is enabled to sweep round the whole periphery of the tubes and over the entire area of the puckers *c* whereas, in the

arrangement illustrated in Fig. 5, it cannot flow in the cells or honeycomb situated immediately below or above the tubes and obstructed by the same, and incomplete use is therefore made of 5 a considerable portion of the heating surface.

In Fig. 7 puckered fins *c* are shown to alternate with corrugated fins *d*, partitioned cells thus being formed.

The relatively large corrugations *d* of the fins 10 illustrated in Fig. 8 are themselves provided with puckers *c*, this result being secured, for example, by firstly puckering the fin and corrugating or folding it again thereafter into larger waves *d*. Though comparatively large, the latter 15 are nevertheless sufficiently close-set to allow tube *a* to pass through several of them in each fin.

An arrangement analogous to that of Fig. 8 is 20 illustrated in Fig. 9, with this difference however that only the large corrugations *d*, or portions of such corrugations touching tube *a*, are provided 25 with puckers *c*, whereas the surface of the remaining corrugations *d* of the fin is smooth.

The single fin illustrated in Fig. 10 is provided 30 with corrugations *e* whose slopes are themselves puckered, as in the two foregoing examples, but in this form of construction said corrugations *e* are so proportioned that only one of them is traversed by each tube *a*. Thanks to the presence of the small puckers *c*, several of which are bisected by tube *a* passing through corrugation *e* of which they are integral the object of the invention is nevertheless fulfilled, since said small puckers increase the area of contact between the fin and the tube.

35 All the forms of fins hereinbefore described may of course be spaced apart or be arranged in contact with each other individually or in groups, the invention extending to every possible disposition permitting each tube to pass through 40 several large or small corrugations of each fin.

From Fig. 4 will be seen the resistance which 45 the edges of the holes *f* in the fins oppose to distortion when the tubes *a* are expanded, and especially to distortion longitudinal of puckers *c*, said resistance being due to the presence at the 50 upper and lower edge of each hole of a sufficient number of said puckers to endow said edges with a high resistance to crushing stresses. Said resistance is further enhanced by forming the fin with a double corrugation, as shown in Figs. 5, and 9 and 10. Tube *a'* has been shown in Fig. 4 by way of example only; and might be varied by being made slightly ovoidal, for example, in order to promote the flow of the streams of 55 fluid at either side of the tubes.

60 Preferably, the fins are formed of aluminium or the like light metals or alloys but the invention is not, of course, limited to the use of any particular metal, nor to the constructional details hereinbefore described and illustrated by way of example.

I claim:

1. In a heat exchange apparatus, parallel tubular members, fins threaded on said tubular

65

members, said fins having corrugations formed therein, said corrugations comprising groups of large corrugations and groups of small corrugations both extending parallel with the direction of flow of the medium surrounding said tubes, said tubular members being expanded internally, said fins gripping the periphery of each of said members along a sinuous line and forming there-with a rigid whole.

2. In a heat exchange apparatus, parallel tubular members, fins threaded on said tubular members, said fins having corrugations and puckers of rounded outline formed therein, said corrugations and said puckers extending parallel with the direction of flow of the medium surrounding said tubes.

3. In a heat exchange apparatus, parallel tubular members, fins threaded on said tubular members, said fins having formed therein groups of corrugations and groups of puckers in alternating relation, said groups of corrugations being located between adjacent tubular members, said groups of puckers being intersected by said members.

4. In a honeycomb heat exchange apparatus, fins having corrugations formed therein, and parallel tubular members passing through a plurality of said fins, said fins being set substantially at right angles to said tubular members and contacting with each other at the apices of said corrugations to form the cells of said honeycomb between said tubes, said corrugations being spaced apart from each other around said tubes.

5. In a heat exchange apparatus, parallel tubular members, fins having small puckers formed therein, and other fins having corrugations formed therein, said fins being threaded upon said tubular members and said corrugated fins alternating with said puckered fins.

6. In a honeycomb heat exchange apparatus, tubular members, and substantially parallel fins threaded upon said tubular members, said fins having formed therein corrugated portions and puckered portions, said corrugated portions being located between said tubular members and contacting at the apices of their corrugations to form the cells of said honeycomb, said puckered portions being located around the points where said tubular members pass through said fins, and said tubular members bisecting a plurality of said puckers in said puckered portions of said fins.

7. In a honeycomb heat exchange apparatus, fins having substantially parallel corrugations formed therein, some of said corrugations being plain and other of said corrugations being puckered, and tubular members passing through said fins, said puckered corrugations being located around the points where said tubular members pass through said fins and said plain corrugations and said puckered corrugations contacting at their apices to form the cells of said honeycomb.

ROBERT MAUTSCH.
